UNITED STATES PATENT OFFICE.

ABRAHAM N. JOHNSON, OF SEATTLE, WASHINGTON, ASSIGNOR OF ONE-HALF TO CAROLINE S. YOUNG, OF SEATTLE, WASHINGTON.

COMBINED SHOULDER-BRACE AND SUSPENDERS.

SPECIFICATION forming part of Letters Patent No. 714,307, dated November 25, 1902.

Application filed April 9, 1902. Serial No. 101,982. (No model.)

To all whom it may concern:

Be it known that I, ABRÁHAM N. JOHNSON, a subject of the King of England, residing at Seattle, in the county of King and State of Washington, have invented certain new and useful Improvements in a Combined Shoulder-Brace and Suspenders, of which the following is a specification, reference being had therein to the accompanying drawings.

10 This invention relates to suspenders and shoulder-braces.

The objects of the invention are, first, to provide a comfortable and efficient shoulder-brace adjustable to suit the figure of any person; second, to provide suspenders which will support the trousers without altering the shape thereof or constraining the movements of the wearer, and, third, to provide a tab which will securely hold the button and furnish an efficient cast-off.

With these objects in view the invention consists in certain novel and peculiar features of construction and combination of parts, as will be hereinafter described and 25 claimed, and in order that it will be fully understood reference is to be had to the accompanying drawings, in which—

Figure 1 is a front elevation, partly in section, of a pair of suspenders embodying my 30 improvements; and Fig. 2 is a side view of a suspender-end and a button attached to a portion of the trousers-band.

Referring by letter, *a* designates hangers, consisting of a body *a*, having three pivots or 35 studs *b* for connecting by attachments *c* the suspender-webbing, of which *d* designates the shoulder-straps, *e* is a cross-brace, and *f* pendant back-straps. The said attachments *c* consist of single pieces of wire provided with a 40 stud-engaging eye *g*, a twisted waist *h*, and bent ends to form tongues *i*, which are inserted in tubes *j*, stitched into loops *k* of the aforesaid web-pieces *d* and *f*. The said cross-brace, preferably elastic, is simply passed around 45 its respective attachment-tubes and is provided with a buckle *l*, whereby the spread of the hangers may be regulated.

A tab *m* is provided for each shoulder and back strap and comprises a continuous piece 50 of wire doubled midway of its length, which is bent up to form a bifurcated hook *n*, the

ends extending upwardly so as to form a button-receiving loop or ring *o*, above which it is twisted, as at *p*, thence bent in opposite transverse directions, and again folded back 55 to form terminal tongues *r*. The said straps pass around tubes *s*, in which tongues *r* are socketed, and are severally provided with a suitable fastening device *t* upon its free end for adjusting reach of suspenders, both front 60 and back, to meet any requirement.

The application of the invention is as follows: Straps *d* are thrown across the shoulders and all the tabs engaged to the trousers-supporting buttons by passing the rings *o* there-over, when the straps, both front and back, are adapted as to lengths, as before described, so that the hangers *a* will be positioned to bear against the shoulder-blades or approximately thereto. The buttons (see Fig. 2) rest 7c upon the bight of the tab-hook, the thread or other securing means passing through the slot *u* thereof, thus preventing all friction or cutting thereat by the supports, and consequently the button remains in place indefinitely. Furthermore, the tabs being made of spring-wire, preferably, the hook ends thereof exert a pressure against the button-face to retain the opposite convex surface of its depression seated in the aforesaid slot, 80 thus preventing any accidental displacement, yet at the same time permits of the ready casting off intact of the suspender-ends by a downward pressure of the thumbs upon the tongue socket-tubes of the tabs. 85

In practice I find that most satisfactory results are obtained in the use of a single button for each of the pendent supports, those in front being located about midway between the front opening and the side seams and the 90 two back ones about two inches in the rear of the said seam, by which arrangement the suspenders must slacken when the wearer stoops or bends forward, and not, as in every other suspenders with which I am familiar, 95 putting an extreme tension upon the back buttons, which is the most frequent cause of "bagging" at the knees when sitting down.

Having described my invention, what I claim as new, and desire to secure by Letters Patent, is—

1. A combined shoulder-brace and suspend-

- ers comprising shoulder-straps, pendent back-straps, a cross-brace, two hangers each provided with three pivotal studs, connections between said hangers and said brace and straps and a button-tab depending from each of said straps, such tab having a button-receiving loop intermediate of its length and a hooked end to prevent the displacement of the button, substantially as described.
- 10 2. A combined shoulder-brace and suspenders comprising shoulder-straps, pendent back-straps, a cross-brace, two hangers each provided with three pivotal studs, connections between said hangers and said brace and straps, means to regulate the lengths of the
- 15

said brace and straps, and a button-tab depending from each of said straps consisting of a continuous wire doubled at its mid-length, said fold bent up to form a hook, the ends formed into a button-receiving loop above 20 which it is twisted and thence making two oppositely-pointed hooks for engaging with the said straps, substantially as described.

In testimony whereof I affix my signature in presence of two witnesses.

ABRAHAM N. JOHNSON.
